MOVABLE MAGNET OSCILLOGRAPH

Jean Babaud, Paris, France, assignor to Etablissements Charles Beaudouin, Paris, France

Application October 11, 1949, Serial No. 120,725
In France October 15, 1948

3 Claims. (Cl. 171—95)

1

This invention relates to oscillograph of the movable magnet type, and its object is to provide a movable magnet oscillograph of new and improved construction, of greatly reduced bulk as compared with conventional apparatus of similar type, while at the same time possessing increased accuracy and capable of retaining over very long periods of time its desirable characteristics of sensibility and precision.

For many years in the construction of certain classes of measuring or indicating instruments bar magnets have been employed; in more recent times however there has been a trend to abandon the use of such bar magnet elements except in the construction of the highly specialized class of laboratory instruments. There are several reasons for this, among which the following may be given: the bar magnet becomes de-magnetized with time; for the lower values of the natural frequency of the instrument satisfactory sensitivity can only be achieved if the magnetic circuit used to create the magnetic field is a circuit including iron therein, but in such case the remanent magnetization of the iron will introduce hysteresis into the circuit; finally, it is difficult to secure uniform damping regardless of the temperature. At the present time however, metal alloys are known having suitable magnetic characteristics for the construction of magnetic vane elements and iron circuits and moreover it has been found that certain substances are adapted to provide a highly successful damping medium.

Thus, it is an object of this invention to provide a movable magnet oscillograph of such construction as to constitute an instrument which will not break easily, which is handy to operate and possesses very reduced dimensions, and comprises a suitable suspending and damping arrangement for a magnetic vane element.

It is another object of the invention to provide an oscillograph of the type described which, on account of the peculiar relative arrangement, to be described, between the magnetic vane element and the field elements thereof, as well as the use of special materials, to be specified, for the construction of the fixed armature and the damping medium, will possess a very high sensitivity and a desirably high fidelity.

According to the invention, an improved oscillograph comprises a body terminating in an armature of reduced diameter serving as a centering means for a circular coil winding which provides the field-generating means, and adapted to receive over the end thereof a carrier means for a movable structure formed with a central op-

tical aperture, said carrier, in cooperation with a disc member of resilient material placed behind it and separating it from the field means, defining a sealed enclosure or chamber in which the movable magnetic structure is suspended and which is filled with a damping fluid.

The metal from which the body forming the armature of the winding is made is a special alloy having suitable magnetic characteristics and especially having low hysteresis, such as ferro-nickel. The vane member forming the movable magnet is made of a metal having a high coercive force such as an aluminium-nickel-cobalt alloy. The damping medium comprises a transparent liquid the viscosity of which does not vary greatly with temperature, such as silicone oil.

The use of the specified materials makes it possible to construct an apparatus which, while having desirable sensitivity and natural frequency characteristics, will be of greatly reduced bulk as compared to what it was possible to obtain heretofore.

The apparatus provided with a magnet vane suspended from a strip or supported on a spring-plate having the amplitude of its movements restricted by limit stops, will provide a highly sensitive and quick-operating polarized signal means.

The above-described and further objects and features of the invention will appear from the ensuing description of one embodiment of the invention, selected for purposes of illustration and not of limitation, with reference to the accompanying drawings, in which:

Figure 1 is a longitudinal section of the apparatus;

Figure 2 is a cross-section on line II—II of Figure 1.

As shown in the drawings, the body 1 of the instrument is formed towards its rear end (toward the left as shown in Figure 1) and for the purpose of mounting it on a support not shown, with a transversely extending notch 2 with which a presser spring 3 and a set screw 4 are associated.

Toward the front or right-hand end (as in Fig. 1) the body 1 is formed with a cylindrical part 5 extended by a core section 6 of reduced diameter, over which an annular coil 7 is seated, the wires 8 of said coil being adapted for connection with a circuit on which measurements are to be effected.

The structure including the cylindrical part 5 and the winding 7 is covered by a sleeve 9 terminating flush with the end of the core and externally formed with a screw-thread 10. This

screw-thread is adapted to receive thereover the rear portion of a bushing 11 provided with an inwardly-directed flange 12 at its front end, said flange being adapted to engage the outer face of a magnet-carrier 13 inserted in said bushing to clamp said carrier against a sealing gasket or disc 14 made of a resilient material, seated against the core and against the end of the sleeve.

The magnet-carrier 13 is formed with a hole extending from its front and axially of the core and opening into a recess containing an optical system 15 comprising for example a simple lens sealingly secured within said recess. The rear part of the magnet-carrier 13 is bored to define a cylindrical chamber 16 sealed rearwardly with the sealing disc 14.

The mirror-carrying vane-shaped magnet member 17 is made of metal having a high coercive force such as an aluminium-nickel-cobalt, a platinum-cobalt, or a silicon-manganese-aluminium alloy, or certain suitable sintered oxides.

It is secured at the center of a torsion strip 18 anchored and soldered at both ends in oppositely-located holes formed in a copper ring 19.

The ring (Fig. 2) is formed with an opening or slot 20 in the vicinity of one of said holes and is weakened in certain sections thereof by being externally milled. The segment 21 tapers down towards its free end adjacent the slot and the strip is soldered after first having placed said segment under tension by imparting a slight camber thereto. The other segment is weakened throughout its extent except at a number of contact bosses 22, so as to concentrate on said segment any bending strains occurring upon the ring being forced into the bore. In this way, the segment 21 will continue to supply the requisite tension since it does not undergo any distortion as the ring is inserted into the bore.

The sealed chamber 16 is filled with a suitable damping fluid, such as silicone oil. The chamber capacity is restricted by the disc 14 and only contains a very small quantity of damping liquid and, owing to the presence of said resilient disc, it may be completely filled, as the resilient disc will allow for any variations in volume of the liquid due to expansion.

The use of special alloys such as the aluminium-nickel-cobalt alloy known as Alnico, for the construction of the magnetic vane, and the use of suitably heat-treated ferro-nickel for the armature, and of silicone oil as a damping medium, make it possible to obtain high accuracy and excellent sensitivity in the apparatus. Thus with a 400 ohm winding, a natural frequency of 180 cycles and a fidelity index of 1%, mirror-displacements of about 190 millimeters per milliampere have been obtained at a distance of one meter.

It will of course be understood that the invention is not restricted to the specific embodiment illustrated and described, given by way of example only. Thus, a similar arrangement could be adopted in constructing a polarized signal means, in which the magnet vane is either suspended to a strip, as in the example shown, or supported on a spring-plate or the like, and its movements restricted by two stops.

10 What I claim is:

1. A movable magnet oscillograph comprising in combination a body of magnetic material forming the armature of an electromagnet with a central core extension, an electrical winding on said core, a sleeve secured to said body around said core, a sealing gasket of non magnetic material against the end of said sleeve and core, a hollow cover against said gasket having a centrally apertured end fitted with a lens and defining a closed chamber in front of said gasket, means tightly clamping said cover with the interposed gasket against said body, an annular fitting of non magnetic material inserted in said chamber and formed with an arcuate peripheral arm, a torsion strip attached under tension between said arm and the diametrically opposed point of said fitting, a mirror carrying vane-shaped magnet mounted on said torsion strip, and a damping liquid filling said chamber.
2. A movable magnet oscillograph according to claim 1, in which in combination the said armature of the electromagnet is of a magnetic material of low hysteresis, such as ferro-nickel, the said vane-shaped magnet is of an alloy having a high coercive force such as an aluminium-nickel-cobalt alloy and the said damping liquid is a liquid the viscosity of which varies but little with temperature, such as silicone oil.
3. A movable magnet oscillograph according to claim 1, wherein the said chamber is cylindrical and said fitting is a split ring, one half of which is tapered in a circumferential direction toward the split, and the other half of which comprises an arcuate segment having a weakened section throughout its length except for three outwardly directed bosses which center said ring in said cylindrical chamber.

JEAN BABAUD.
